(57) **CLAIM**

I claim the ornamental design for a display screen with graphical user interface, as shown and described.

DESCRIPTION

FIG. 1 is a front view of a first image of a first display screen with graphical user interface showing my new design; FIG. 2 is a front view of a second image of the first display screen, whereby the image appearance transitions sequentially between the images of FIGS. 1 and 2; FIG. 3 is a front view of a first image of a second display screen with graphical user interface; and,

FIG. 4 is a front view of a second image of the second display screen, whereby the image appearance transitions sequentially between the images of FIGS. 3 and 4.

The broken lines depict portions of the graphical user interface that are for environmental purposes only and form no part of the claimed design.

The appearance of the transitional image sequentially transitions between the images shown in FIGS. 1-2 and 3-4. The process or period in which one image transitions to another image forms no part of the claimed design.
